CLAIM

The ornamental design for a toss game board assembly, as shown and described.

DESCRIPTION

FIG. 1 is a perspective view of a toss game board assembly according to the present invention.

FIG. 2 is a left side end view of the toss game board assembly shown in FIG. 1.

FIG. 3 is a right side end view of the toss game board assembly shown in FIGS. 1 and 2.

FIG. 4 is a left side view of the toss game board assembly shown in FIGS. 1-3.

FIG. 5 is a right side view of the toss game board assembly shown in FIGS. 1-4.

FIG. 6 is a top view of the toss game board assembly shown in FIGS. 1-5; and,

FIG. 7 is a bottom view of the toss game board assembly shown in FIGS. 1-6.
